UNITED STATES PATENT OFFICE.

CHARLES T. SCHOEN, OF ALLEGHENY, PENNSYLVANIA.

DESIGN FOR A POST FOR LETTER-BOXES.

SPECIFICATION forming part of Design No. 22,432, dated May 9, 1893.

Application filed March 23, 1893. Serial No. 467,376. Term of patent 14 years.

To all whom it may concern:

Be it known that I, CHARLES T. SCHOEN, a citizen of the United States, residing at Allegheny, in the county of Allegheny and State of Pennsylvania, have invented and produced a certain new, useful, and original Design for Posts for Letter-Boxes, &c., of which the following is a full, clear, and exact description.

The object of this invention is to provide a design for a post to receive and support street letter boxes in which the elements of great strength and gracefulness are apparent.

In the accompanying drawings illustrating my design, Figure 1 shows the post complete in elevation, and Fig. 2 is a cross-section of the post alone.

The post is made tapering from end to end

and is provided with longitudinal reedings *a*, as best seen in Fig. 2, and is also provided with the horizontal earth-line flange *b*, and ²⁰ the horizontal top flange *c*.

The essential features of the design are the end to end taper and the longitudinal reedings.

What I claim is—

The design for street letter box posts, substantially as shown and described.

In testimony whereof I have hereunto set my hand this 22d day of March, A. D. 1893.

CHARLES T. SCHOEN.
